(57) **CLAIM**

The ornamental design for an air spa container, as shown and described.

DESCRIPTION

FIG. 1 is an upper perspective view of an air spa container showing my design in a condition of use.

FIG. 2 is another upper perspective view thereof;

FIG. 3 is a front elevation view thereof;

FIG. 4 is a back elevation view thereof;

FIG. 5 is a side elevation view thereof;

FIG. 6 is an opposite side elevation view thereof;

FIG. 7 is a top plan view thereof; and,

FIG. 8 is a bottom plan view thereof.

The broken lines in FIG. 1 represent environment and are for illustrative purposes only. The broken lines form no part of the claimed design.
